UNITED STATES PATENT OFFICE.

FRANK D. POWELL AND CHARLES S. ELLIS, OF CHICAGO, ILLINOIS, ASSIGNORS TO AMERICAN COIN REGISTER COMPANY, OF CHICAGO, ILLINOIS, A CORPORATION OF ILLINOIS.

COIN-REGISTERING MECHANISM.

No. 880,571.

Specification of Letters Patent.

Patented March 3, 1908.

Application filed June 20, 1904. Serial No. 213,326.

To all whom it may concern:

Be it known that we, FRANK D. POWELL and CHARLES S. ELLIS, citizens of the United States, residing at Chicago, in the county of Cook and State of Illinois, have invented certain new and useful Improvements in Coin-Registering Mechanism, of which the following is a description, reference being had to the accompanying drawings, forming a part of this specification, in which corresponding letters of reference in the different figures indicate like parts.

Our invention relates to coin registering mechanism adapted to be used in connection with telephones, vending machines and for other analogous purposes, the object thereof being among other things, to provide an automatic registering mechanism which shall be protected against unauthorized manipulation, said mechanism being so constructed as to receive and positively transmit a coin or coins of the same or different denominations to a locked or sealed coin-receptacle and properly register the same.

A further object is to provide a signal to be automatically operated, preferably in conjunction with said registering mechanism, which signal shall be sounded once upon the deposit of each coin representing a predetermined unit of value and once for each of such units represented by larger coins if used.

Further subsidiary or more specific objects are to provide means for preventing the withdrawal of a coin when once deposited within the device and before it shall have reached the coin-receptacle; to operate the device from without by positive means, but only through the intervention or upon the introduction of a proper coin; to provide means for the rejection of improper coins; to render the machine inoperative for the reception of a second coin until a coin previously introduced shall have been deposited within the coin-receptacle and properly registered; to render it inoperative for the reception of a coin at all times except when the primary actuator is in its normal position; to prevent the registration of a coin until after its deposit in the coin-receptacle; to provide means for automatically projecting one or more sections of a continuous recording strip or tape into the coin receptacle in conjunction with a coin representing one or more predetermined units of value; to provide means for automatically severing such strips by the act of opening the

coin receptacle; to provide means for shielding the severed end of the strip remaining within the primary or registering compartment while the coin receptacle is open; to provide means for automatically severing any portion of the registering strip projecting within the coin-receptacle as a result of removing the registering mechanism and generally, for guarding against any improper or irregular manipulation of the device or of a given part thereof, by those having access to another part. To these ends, our invention consists in the several combinations of elements hereinafter more particularly described and definitely pointed out in the claims.

In the drawings Figure 1, is a perspective view of a coin registering mechanism embodying the features of our invention, portions thereof being broken away to show the locks for the separate compartments. Fig. 2, is a front elevation thereof, the detachable covering plate being removed to show the interior mechanism. Fig. 3, is a sectional view taken upon the line 3—, Fig. 2, viewed in the direction of the arrow there shown. Fig. 4, is a like view taken upon the line 4—, Fig. 2, viewed in the direction of the arrow there shown. Fig. 5, is a like view taken upon the line 5—, Fig. 2, viewed in the direction of the arrow there shown, Fig. 6, is a like sectional view in detail of a portion of the device shown in Fig. 5, the parts being indicated in different positions to represent the manner in which the registering mechanism is locked when the coin receptacle is open. Fig. 7, is a plan view of the coin actuating rollers and a portion of the operating mechanism connected therewith. Fig. 8, is a longitudinal sectional view of said rollers, taken upon the line 8—, Fig. 3 viewed in the direction of the arrow there shown. Fig. 9, is a transverse sectional view of the coin rollers taken upon the line 9—Fig. 7, viewed in the direction of the arrow there shown, a coin being indicated in position to enter the rollers. Fig. 10, is a like view showing the rollers in different relative positions with the coin as it would appear when passing them, Fig. 11, is a like sectional view taken upon the line 11—, Fig. 7, viewed in the direction of the arrow shown there, a coin of different denomination being shown about to enter between the rollers. Fig. 12, is a like view showing the parts in different relative posi-

tions with the coin between the rollers. Fig. 13, is a like sectional view taken upon the line 13—, Fig. 7, viewed in the direction of the arrow there shown, together with a coin 5 of a still different denomination as it would appear when about to enter between the rollers. Fig. 14, is a like view showing the coin further advanced. Fig. 15, is a view, partly in section of the record printing mechanism, taken upon the line 15—, Fig. 2, viewed in the direction of the arrow there shown. Fig. 16, is a sectional view of the printing rollers taken upon the line 16—, Fig. 18, viewed in the direction of the arrow 10 there shown, Fig. 17, is a like view taken upon the line 17— Fig. 18. Fig. 18, is a transverse sectional view of portions of the printing rollers, Fig. 19, is a view of a portion of the registering tape and carbon or 15 impression paper, showing the manner in which the impressions are made thereon, Fig. 20 is a plan view of the coin chutes, Fig. 21, is a perspective view in detail of the spring-controlled device for detachably holding the registering mechanism in position 20 within the case and for severing the recording strip when said mechanism is removed, as well as when the coin-receptacle is opened, and Fig. 22, is a perspective view of the dog 25 for locking the registering mechanism when the coin receptacle is open.

Referring to the drawings, 1 represents the case generally, which is preferably formed from sheet-metal, said case being divided 35 into an upper and lower compartment, said compartments being separated by means of a horizontal partition 2. The upper compartment is adapted to receive the coin chute, registering and signal mechanism, 40 which is mounted within a suitable frame adapted to be removably secured therein as hereinafter described, and is rendered accessible by means of a removable front-plate 3, which may be secured in place by means 45 of dowels 4, at the top, Figs. 3, 4 and 5, passing through bores in lugs 5, attached to the inner face of the case and similar dowels, not shown, adapted to enter bores in the plate 2. A lug 6, Fig. 1, is rigidly attached to the inner face of the plate 3 in position to be 50 engaged, when said covering plate is in place, by the bolt 7 of a lock 8, also shown in Fig. 2, attached to the end plate of the case. The throwing of said bolt serves to securely lock 55 said plate in position.

The lower portion 9, of the case, which is rigidly attached to the plate 2, is made semi-cylindrical in form and is adapted to partially inclose a hollow cylindrical coin-receptacle 10, which is centrally pivoted or journaled therein at its respective ends. The lower portion of the depending part 9 of the casing is cut away as shown at 11, Figs. 1, 2, 3 and 4, to expose a portion of the coin-receptacle, while an opening 12, Figs. 3, 4 and 5 is

formed in said coin-receptacle to permit of access thereto. Said cylinder is provided with a stop or projection 13 upon its periphery which is adapted to engage the edges 14 and 15 respectively of the opening 11 in the outer case, thereby limiting the extent of rotation of said cylinder. Said stop is so placed with respect to the opening 12, that when it is against the part 14, as shown in the several figures referred to, said opening will 70 be closed, but when in the reverse position, said opening will be brought opposite to the opening 11 of the case so as to permit access to the coin receptacle. A lock 16, Fig. 1, the key-hole of which coincides with the axis of 75 said cylinder, is attached to the inner end of the cylinder in such a way that when the cylinder is in its normal position, the bolt 18 of the lock may be thrown so as to engage an opening 19 in the plate 2, thereby locking the 80 receptacle in a closed position.

Located within the upper compartment of the case is a frame-work consisting of a base-plate 20, Figs. 2 to 5, inclusive, and end up- 85 rights 21 and 22 which are integral therewith, said base-plate being arranged to rest upon the plate 2. Said uprights are also shown in Figs. 7 and 8. Supported in the frame-plate or uprights 21, 22 is a horizontal 90 shaft 23, which is passed loosely through elongated slots 24, 24, Fig. 8, in said uprights and thence through a bore adapted to fit said 95 shaft, formed in movable plates 25, 25, better shown in Figs. 7 and 8, which plates are attached to the uprights 21, 22, by means of 100 screws 26, 26 passing through a slot 27, Fig. 8, in one end of each of the plates 25, the other end of each of said plates being bent at right angles to its body as shown at 28, 28. Lugs 29, 29, are formed upon the rear of said 105 uprights at the upper ends thereof, which are parallel with the parts 28. Guide pins 30, 30, are rigidly attached to the parts 28, and passed loosely through the bores in the lugs 29. Spiral springs 31, 31, are interposed between the parts 28 and 29, being supported 110 by means of the pins 30. Said springs tend to hold the shaft 23 normally against the lower ends of the slots 24, while the slots 27, permit an opposite movement of said shaft 115 against the action of said spring in the manner and for the purpose hereinafter described. The right hand end of the shaft 23 is sufficiently extended to project through the walls of the casing 1, for the reception of a crank 120 32, having a sleeve 33 which is rigidly attached to said shaft within the walls of the casing 1, by means of a pin 34, which projects sufficiently, as shown in Fig. 2, to limit the backward movement of said crank by engagement with the part 28, and the forward movement thereof by engagement with a pin 35, upon the upright 22.

Rigidly mounted upon the shaft 23 and secured thereto by means of a pin 36, Figs. 7 130

and 8, is a roller 37, which forms a novel and important feature of the primary coin actuator. Said roller is provided with a series of peripheral grooves 38, for the purpose hereinafter stated. Arranged parallel to shaft 23 and mounted in suitable bearings in said uprights, is a shaft 39, upon which is loosely mounted a roller 40, said roller being arranged to permit a varying but limited movement of the shaft therein in the manner and for the purpose hereinafter stated.

The rollers 37 and 40 are caused to rotate in unison by means of gears 41, 42, rigidly attached to the ends of said rollers respectively, by means of pins 43, 44, Fig. 8. Ratchet wheels 45, 46 are mounted upon the shaft 23, the former being rigidly attached thereto by means of a pin 47, Fig. 8, and the latter being fastened to the roller 37 by means of the pin 20 43. Spring pressed pawls 48, 49, Figs. 3, 4, 5 and 7, are in position to engage said ratchet wheels respectively when the shaft 23 is moved to an abnormal position against the action of the springs 31. Pins 50, 50, one of 25 which is shown in Fig. 3, being secured in the frame-plates to hold said pawls normally out of engagement with said ratchet wheels. The object of this feature, is to permit the crank to be moved to its full limit in either direction 30 when no coin is present, as well as to prevent a backward or reverse movement of the rollers after a coin is introduced and in engagement with the rollers, thus guarding against a possible abstraction of the coin in 35 transit and after registration, which feature will be more fully referred to hereafter.

Mounted upon the protruding end of the shaft 23, is a coiled spring 51, Figs. 2, 7, and 8, one terminal of which is attached to said 40 shaft in any well known way and the other to the frame-plate 21. The purpose of said spring is to return the roller 37 to its normal position, which is determined by means of a stop pin or projection 52, Fig. 3, rigidly attached to a hub upon the gear 42, and in position 45 to engage a stop-pin 53, shown in section in said Fig. 3, which pin projects laterally from the inner face of the frame-plate or upright 22. The gear 41 being rigidly connected with the shaft 23 and in mesh with the gear 42, it follows that the stop 52 will be held normally against the stop 53, thereby retaining the crank handle 32 in the 50 normal position shown in Fig. 1. Said stop-pins not only serve to position the rollers but the handle as well, which cannot be moved farther back than the position shown in Fig. 1, when the rollers and stop-pins are in the relative position shown in Fig. 3. We prefer, however, in order not to place any undue strain upon the working parts, which might result from careless or malicious use, to provide stop-pins or lugs 54, 55, Fig. 1, upon the outside of the case to limit the 55 movement of the crank. The crank should

have a sufficient movement to enable the largest of the several coins provided for to pass between the rollers and be discharged therefrom. Assuming such a coin to be a quarter of a dollar and the rollers, to be of 70 substantially the proportions indicated, the crank would describe about one-third of a revolution in order to cause the discharge of the largest coin.

It is desirable that the rollers 37 and 40 75 which we prefer to designate as the "coin-rollers", should be made of metal, preferably steel, and that the surfaces thereof should be smooth in order not to injure the coins. Inasmuch, however, as the space between the 80 rollers is less than the thickness of a coin and it being necessary to provide a spring pressure upon the rollers in order to feed the coins, it follows that the latter would not enter the rollers if the entire peripheral surface thereof were smooth. We therefore, provide a longitudinal groove 56, Figs. 4, 7 and 9, to 14 inclusive, in the roller 37, the edges of which are so rounded and smoothed as not to abrade or mark the entering coin. 85 This groove is adapted to co-act with other elements about to be described in connection with the roller 40, which latter, as stated, is loose upon the shaft 39 so as to have a limited rotation thereon. The roller 90 40 is provided with a series of transverse notches 57, 58, and 59, Figs. 2 and 7 to 14 inclusive, each of which is of a depth sufficient to cut away nearly two-thirds of the transverse section of the roller, as clearly shown 95 in said last named figures. In each of said notches there is pivoted at 60, a curved arm 61, the pivoted point of each of said arms being in a common radial plane. Radial bores 62, Figs. 7 and 9 to 14, are formed in 100 said rollers into which are inserted spiral springs 63, which bear against the inner edges of said arms and tend to push them outwardly beyond the periphery of the roller as shown in Figs. 2, 4, 9, 11 and 13, and the 105 purpose of the grooves 38 in the roller 37 is to receive such of said arms as is not acted upon by a coin when the crank is actuated. The curve of the outer face of each of said arms during the greater portion of its length conforms to that of the periphery of the roller. A short distance from the pivoted point of 110 each of said arms there is formed a shoulder 64, which is so placed that when said rollers are in their respective normal positions, said shoulders will be opposite to the groove 56 in the roller 37, as shown in Figs. 9, 11 and 13. Formed upon each of said arms is an inwardly projecting detent 65, and in the shaft 39, corresponding to the location respectively 115 of the notches 57, 58 and 59, are a series of radial pins 66, 67 and 68 Figs. 9 to 14, of uniform length, each of which is adapted to be engaged by one of said detents when the arm 61 is pushed against the action of the spring 120 130

63, as hereinafter stated, and the crank arm 32 is moved, but to escape such contact when said arms respectively are in their normal positions.

5 It will be observed by reference to Figs. 9, 11 and 13, which represent the coin rollers in their normal positions, that the pins 66, 67 and 68 are located in different radial planes with respect to each other. This is an important feature inasmuch as the normal position of a given pin with respect to the normal position of the detent, must bear a fixed relation to the value of the coin to be inserted opposite to a particular arm as hereinafter stated.

10 Mounted upon the left hand end of the shaft 39, Figs. 2, 7 and 8, is a spiral spring 69 one terminal of which is attached to the frame piece 21 as shown, while the other is secured in a slot in the end of said shaft in such a way that it tends to cause the shaft to rotate in a direction opposite to that of the shaft 23. An irregular shaped part, generally designated by 70 Figs. 2, 3, 4, 5, 7 and 8 20 and having a sector gear 70^a formed thereon, is rigidly attached to the shaft 39 by means of a pin 71, Figs. 7 and 8, in which gear is formed a curved slot or opening 72, concentric with the axis of said gear, through which slot 30 the hub of the gear 45 upon the shaft 23 is passed. Said slot therefore, by contact with said hub, serves to limit the rotary movement of the shaft 39, the normal position of which is indicated in Figs. 3, 4, 5, 9, 11 and 35 13, in which position it is yieldingly held by means of the spring 69.

15 The spring controlled shaft 39, and the part bearing the segmental gear, serve to actuate the registering and signal mechanism 40 which will be more fully explained after describing the means for introducing and depositing the coins.

20 Formed in the top of the case are coin slots 73, 74 and 75, Fig. 1, adapted for the reception of quarters, dimes and nickels respectively, said slots being indicated to the user by means of the several figures "25", "10" and "5", formed upon a proper plate adjacent thereto.

25 Located within the case and supported by means of members 76, 77, Figs. 2, 3, 4, 5 and 20, which are attached to the main frame, is a framework generally designated by 78, in which is provided a series of coin-chutes leading to the coin rollers. Ways 79, 80 and 81, Figs. 2, 3, 4 and 20 separated by vertical flanges 82, 83, are arranged in juxtaposition to and coincident with the coin-slots in the case and communicate with coin-depressions 30 or receptacles 84, 85 and 86 respectively, Figs. 20, having semi-circular walls the diameter of which is slightly larger than that of the respective coins adapted to be placed therein. The bottom of said coin depressions 65 is flush with inclined ways or chutes each of a

width corresponding to that of the proper coin and each being provided for a short distance with side ledges 87, Fig. 20, to support the coin, while an intermediate opening 88, permits an improper coin to fall through into any suitable receptacle or by-pass, not shown, without reaching the coin-rollers. The lower portion of the chute 89, is protected by means of a housing 90, Figs. 4 and 20 and curved downwardly as shown in Fig. 4, 75 into the bight of the rolls, notches 91, Figs. 2 and 20, being formed therein to receive the arms 61.

80 Beneath the coin rollers is a coin chute 92, Figs. 2, 3 and 4, which is sufficiently wide at the top to receive any one of the several coins which may be discharged from said rollers. Said chute communicates with a coin-slot 93, Fig. 4, cut through the base-plate 20 and division plate 2 and communicating with the opening 12 of the coin receptacle 10. A flange 94, Figs. 3 and 4, attached to the bottom of the plate 2, serves to direct the coin into said receptacle.

85 The registering mechanism is supported by means of two parallel frame-plates 95, 96, Figs. 2, 3, 4, 5 and 15, which are connected by means of studs 97, or in any well known way, the plate 96 being rigidly attached by approved means not shown, to the outside of the frame-plate 21. Supported in bearings in the frame-plates 95, 96, is a shaft 98, upon which is rigidly mounted a feed-roller 99. Said shaft is extended through the frame-plate 96, and has rigidly attached to its outer end a bent lever, generally designated by 100. Said lever has an upwardly extended arm 101, into a longitudinal bore in which, as shown in section in Fig. 5, is inserted in a sliding pin 102 which is projected by means of a coiled spring 103. A small stop pin 104 attached to the pin 102 and projecting through a slot 105, serves to limit the movement of said sliding pin. A stop-pin 106, Figs. 2, 3 and 4, serves to limit the backward movement of the lever arm 101. The end of the pin 102 is beveled as shown at 107, Fig. 5, which beveled portion lies in the path of movement of a series of pins 108 projecting laterally from the outer face of the part 70, as shown in Figs. 2, 3, 4 and 5. The beveled portion 107 of the pins 102 is so formed that when the shaft 39 is so rotated as to move the part 70 into an abnormal position, the contact of each pin in succession will cause the pin 102 to be pushed back against the action of the spring 103, thereby enabling said pins to pass in the direction stated; but when the movement of the shaft is reversed, the contact of said pins will cause the movement of said lever arm until the pin slips off from the part 102, thereby enabling the lever to be restored to its normal position against the pin 106 by the action of the spiral spring 109, one end of which is attached to the plate 96 and

110 115 120 125 130

the other to the depending arm 110 of said lever. A spring pressed pawl 111, Figs. 5 and 15 is pivotally attached to the inner face of the lever arm 110, in position to engage 5 the teeth of a ratchet wheel 112, attached to the end of the feed roller 99. A second spring pressed pawl 113, is pivoted to the plate 96 also in position to engage and prevent the backward movement of said ratchet 10 wheel. The reverse movement of each of the pins, 108, causes a vibration of said lever and the consequent movement of the ratchet-wheel 112 and feed roller 99 one step with the passage of each of said pins.

15 Mounted upon a pin 114, Fig. 15, projecting from the frame plate 21 is a spool 115, upon which is wound a registering tape 116 together with a carbon or impression tape 117, see also Figs. 2 and 19, which tapes or 20 strips are passed over a guide-plate 118, Fig. 15, and thence into a guide way 119, which leads into the bight between the feed roller 99 and a compression roller 120, Figs. 5 and 15, which is mounted in a frame 121 supported by means of a rod 122 passing through 25 a bore in a plate 123 rigidly attached to the frame. A spiral spring 124, upon said rod serves to press the roller 120 against the paper strips in contact with the feed roller 99. A second guide, 125 beneath said rollers, shown also in Fig. 5, serves to pass the paper strips downwardly to an opening 126, through which they pass into the coin receptacle 10.

30 The feed roller 99 is provided with two parallel circumferential rows of teeth 127, Figs. 16 and 18, which enter corresponding depressions 128 in the compression roller 120. Said teeth pass through both paper strips 35 thereby insuring their uniform passage through the rollers. Between said teeth upon the periphery of the feed roller 99 is formed a series of raised characters or signs 129, Figs. 17 and 18, which are intended to 40 register upon the tape the value of each coin as it is deposited. The mark ordinarily employed is a mere dash as shown at 130 upon the tape 116, Fig. 19, but in order to enable them to be readily counted, we prefer to substitute a distinguishing character, such for 45 example as "x", for every tenth mark as shown at 131, and a number as shown at 132, for every twentieth mark. This number may be any arbitrary one but is preferably 50 the distinctive number of the machine in which the strip is employed. A signal mechanism is operated at the same time with that which causes registration. Upon the arm 110 of the lever 100 is a laterally projecting 55 lug 133, Figs. 2 and 5, having a slot therein into which is loosely inserted one arm or terminal 134 of a spring tempered wire, the body of which is coiled around a stud 135 upon the plate 20. Upon the other arm 136 60 is a hammer 137, in proximity to a bell 138,

supported upon the base-plate. A pin 139 is provided to limit the movement of the arm 136 and hold the hammer normally out of actual contact with the bell. The movement of the lever 100 through the action of 70 the pins 108, causes the hammer to strike the bell once for each coin of minimum value, and once for each of such units of value represented in coins of higher denominations.

It is important that the signal should be 75 operated so as to enable the hammer strokes to be readily counted and hence we provide means for retarding the speed of the shaft 39 in its reverse movement, for the purpose hereinafter described in the explanation of 80 the operation of the machine. This result is accomplished by means of the segmental gear 70^a which meshes into a pinion 140, Figs. 2 and 5, upon a shaft 141, also shown in Figs. 3 and 4. Upon said shaft is rigidly mounted 85 an escapement-wheel 142, which is arranged to operate in the usual well known way with a pallet 143, Figs. 2 and 3, having a bent arm 144 rigidly attached thereto, which arm is provided with an adjustable weight 145, 90 upon its free end. In order to permit a rapid and free initial movement of the segmental gear, the pinion 140 is made loose upon the shaft but is rigidly attached to a ratchet wheel 146, Fig. 2, also loose upon the shaft, 95 which latter is adapted to be engaged by a spring pressed pawl not shown, upon the side of an arm 147, which is rigidly attached to said shaft. This well known form of mechanism permits the pinion to slip when the 100 gear 70^a is rotated in one direction and causes it to rotate said shaft and actuate the escapement mechanism, when the movement is reversed, thus serving to retard the movement of the pins 108 in their contact with the lever 105 100.

In order to prevent the destruction, by dishonest persons, of a portion of the registering strip and the abstraction of a corresponding number of coins when the coin receptacle 110 is opened, we cause said strip to be numbered upon the opposite side from that upon which the registration is made with a series of consecutive numbers placed to correspond substantially to the respective position of the 115 registering marks, in the manner shown at 148, Figs. 1, 2 and 19. Said strip is conducted past a window 149, Figs. 1, 3, 4, and 5, formed in the outer case, through which said numbers can be seen from without.

In order to guard further against improper manipulation of the registering strip, we provide means for automatically severing that portion which may have entered the coin receptacle from that which precedes it, as a 125 result of opening said receptacle. This is accomplished as follows: Upon the front edge of the opening 126, Figs. 5 and 21, there is formed a series of knife-edged serrations 150 adjacent to the path of the tape. A 130

counterpart serrated cutter 151, is attached to the back edge of the opening in the cylindrical receptacle 10 in position to coact with the part 150. Upon unlocking the coin receptacle and rotating it to give access to the opening therein, the cutter 151 is caused to pass the cutter 150, thereby severing the strip and so shielding the unused portion of the strip by the cylindrical wall of the receptacle, as to effectually prevent access thereto through said receptacle. It is further desirable that no registration of the coin should occur before its entry into the coin receptacle or while said receptacle is open; and in order 15 to accomplish this result, we cause an opening 152, to be formed in the plate 2 in the plane of the lever 100, as shown in Figs. 5 and 6, in which opening is pivoted a gravity dog 153, Figs. 2, 3, 4, 5, 6, and 22. Said 20 dog is provided with an arm 154, extending laterally therefrom and when the coin receptacle is in its normal closed position, said arm is caused to hang loosely into a notch 155, as shown in Fig. 5, at which time the upper end 25 of the dog is in such a position that the lever arm 110 may vibrate without touching it; but upon opening the coin receptacle, the part 154 is caused to ride up upon the inner face of the notch 155, thereby tilting the 30 upper end of the dog and causing it to be brought into locking engagement with the lower end of the lever arm 110 as clearly shown in Fig. 6, in which position it is securely held by the walls of the cylinder 10. 35 While the parts remain in the position last described, a coin, if introduced and passed through the rollers, could not enter the receptacle, nor would it be registered until after the closing of the receptacle, when the 40 coin would fall into it, the lever 100 would be released and proper registration would be made.

As before stated, the entire registering and signal mechanism is made so as to be readily 45 removable from the case, but in order to prevent possible collusion and fraud, it is desirable that the registering strip within the coin receptacle should be automatically severed before such removal can occur. 50 This is accomplished as follows: Upon the inner end wall of the case is pivoted at 156, Fig. 21, a lever 157, also shown at the left in Fig. 2. A coiled spring 158, one end of which is attached to the rear end of said 55 lever and the other to the frame, serves to hold said lever in a normal position. A notch 159 is formed in said lever which is in position to engage a pin 160, Fig. 2, projecting laterally from the frame. In order to 60 place the frame within or to remove it from the case, it is necessary that the front end of the lever should be raised against the action of the spring 158 to enable the pin to enter the notch. Bent downwardly and forwardly from the rear and integral therewith

is a part 161, having a serrated cutter 162 upon its upturned edge. Said cutter is held normally in a position so as not to interfere with the action of the cutter 151, Fig. 5, but so adjusted that when the lever 157 is tilted to release the framework from the case, the cutter 162 will move forward past the cutter 150 and sever the registering strip, thereby preventing collusion between the attendant who may have authorized access to the mechanism and the one having access to the coin receptacle. 70

Having thus described the various parts of our improved machine, we will now explain its operation: A nickel having been 80 deposited in the coin slot 75, Fig. 1, it is carried by gravity down the chute into the bight of the rollers 37, 40, as shown in Fig. 9, in which 162 represents the coin. The edge of the coin is engaged upon one side by the 85 notch 56, and upon the other by the shoulder 64 of the protruding arm 61. The handle of the crank 32 is then grasped by the operator and moved downwardly to its full limit, thereby causing the coin to be passed 90 through between the faces of the rollers and discharged into the coin chute 92, from whence it passes into the coin receptacle 10. As the coin enters the rollers, it causes them to separate as shown in Fig. 10, the roller 37 95 being pushed back against the action of the spring 31 at the end of the roller in which the coin is located, to a sufficient extent to cause the pawl 49 to be brought into engagement with the ratchet wheel 46, thereby preventing a backward movement of the crank until after the discharge of the coin. It should be borne in mind that the teeth of the gears 42 and 46 should be of sufficient length 100 to allow for the separation of the rollers without causing the gears to become disengaged. As the coin enters between the rollers, it causes the curved arm 61 opposite thereto, to be pressed back against the action of the spring 63, until the detent 65, is in position 110 to engage the pin 68, at the proper time. The rollers 37 and 40 are caused to rotate in unison by means of the gears 41, 42, but during the early part of such movement, the shaft 39 is at rest, being held in a normal 115 position as stated by means of the spring 69. The position of the pin 68, in the shaft 39 bears a fixed relation to the pins 108, which actuate the registering mechanism; and it is essential that said pin be so placed that it 120 will not engage the detent 65, until the roller 40 shall have completed a considerable portion of its partial revolution in order that the shaft 39 may be caused to rotate just far enough to cause the first of the series of pins 125 108 to engage and pass the pin 102, Fig. 5, in the arm 101 of the registering lever by pushing said pin into its socket. As the coin is released from the rollers the spring 63 causes the arm 61 to be restored to its normal posi- 130

tion, thereby releasing the detent 65 from engagement with the pin 68 when the spring 69 causes the shaft 39 to be reversed and restored to its normal position. This action causes the first of the series of pins 108, in its backward movement, to engage the pin 102 upon its opposite side from that of the beveled face 107; and as the pin is so shaped upon that side that contact therewith will not force it into its socket, the lever 100 is vibrated thereby until the pin 108 slips off from the pin 102, when the lever is returned to its normal position by the action of the spring 109. The vibration of the lever causes the feed rollers 99 to be advanced one step, thereby impressing one mark upon the registering strip and moving a corresponding section thereof into the coin receptacle, while at the same time, a single stroke of the hammer is made upon the bell. Should a dime be deposited in the proper slot, the action would be the same in every respect except that by reason of the relative position of the pin 67, upon the shaft 39, the movement of said shaft would be sufficient to cause two of the pins 108 to be brought into contact with the lever, thereby vibrating the latter twice, moving the feed roller two steps and sounding two strokes upon the bell.

In Figs. 13 and 14, it will be noted that the pin 66 is placed very near the detent 65 so that the two will be brought into engagement as soon as the coin 164, which represents a quarter, is fully grasped by the rollers, thereby rotating the shaft 39 to its full limit and causing all of the five pins to engage the lever, thus vibrating it five times and moving the strip and actuating the signal correspondingly. The smooth peripheral surface of the coin rollers prevents them from receiving and passing a second coin, should one be introduced into a coin chute, during the passage of another through the rollers; nor can such action occur until the first coin is discharged and the rollers are returned to their respective normal positions. This feature prevents the introduction of a coin without registration.

From the foregoing it will be seen that, while the machine described is applicable only to three different coins, it may if desired, be utilized for coins of all denominations by merely increasing the length of the rollers, the number of coin chutes, the number of registering pins and adjusting the additional pins upon the shaft by which the latter are directly controlled. We do not, therefore confine ourselves to a construction limiting the machine to any particular number of coins as it is obvious that it may be utilized with one or more, nor do we confine ourselves to the specific construction shown in other particulars. It is obvious that the coin feeding rollers may be used with coins of one denomination only and

with any kind of mechanism to register or in any manner indicate the passage of a coin, and while we have shown and prefer to use a registering mechanism in which a continuous registering tape or strip, similar to that described in our previous patent No. 754,553, of March 15th, 1904, is employed, we do not wish to be limited thereto.

Having thus described our invention, we claim:

1. In a device of the class described, the combination of a coin-chute and coin receptacle, of interposed yielding coin feed rollers and a coin-controlled signal for indicating the values of coins of different denominations in predetermined units of value. 75

2. In a device of the class described, the combination with a coin receptacle of a plurality of coin-chutes for coins of different denominations, interposed coin feed rollers for positively feeding the same to said receptacles and a coin controlled signal for indicating the value in units of the several coins fed thereto. 85

3. In a device of the class described, the combination with a coin receptacle of a plurality of coin-chutes for coins of different denominations, interposed yielding coin feed-rollers for positively feeding coins to said receptacle, coin-controlled means for limiting the extent of rotation of said rolls in proportion to the unit of value of the coin deposited, a coin-controlled signal for indicating by sound the value in units of the several coins fed thereto, and a coin-controlled registering mechanism for simultaneously registering said unit values. 95

4. In a device of the class described, the combination with a coin receptacle of a plurality of coin-chutes for coins of different denominations, interposed means for positively feeding the same to said receptacle, a coin-controlled registering mechanism for registering the unit values of the several coins deposited, and means for automatically depositing the evidence of registration made thereby in said coin receptacle. 105

5. In a device of the class described, the combination with a sealed or locked receptacle, of coin feed-rollers protected against unauthorized manipulation, means for actuating said rollers in unison, means for limiting the rotary movement thereof, means for preventing a backward movement thereof after the engagement thereby with, and before the discharge of a coin in their backward movement, and means for causing a backward movement to a normal position after the discharge of each coin. 115

6. In a device of the class described, the combination with a sealed or locked coin receptacle, of coin feed-rollers protected against unauthorized manipulation, for feeding coin to said receptacle, one of said rollers having a longitudinal groove in its periphery, 125

means for automatically reversing the action of said rollers after the discharge of a coin, means for yieldingly maintaining said rollers in a normal position with said grooves in the 5 bight of the rollers, and means for preventing a backward movement of said rollers during the passage of a coin.

7. In a device of the class described, the combination of a coin receptacle, of coin 10 feeding rollers arranged to rotate in unison, one of said rollers being mounted in spring-controlled yielding bearings whereby the passage of a coin may cause their separation, and normally inert means for engaging and 15 preventing the backward movement of said rollers while so separated.

8. The combination with a coin-receptacle of coin rollers arranged to have a limited forward and backward rotary movement in 20 unison, means for normally maintaining said rollers in an initial position, means for locking them against backward movement while a coin is interposed between them, and means for releasing said locking means upon 25 the discharge of the coin.

9. In a device of the class described, the combination with a sealed or locked coin receptacle, of coin feed-rollers, separate means for feeding coins of different denominations to said rollers, an actuator common 30 to all of said ways, means controlled by said actuator for indicating the respective unit values of the different coins, and means in the pathway of each coin controlled by the 35 passage of a coin therein, for separately moving said actuator a predetermined distance.

10. In a device of the class described, the combination with a sealed or locked coin receptacle, of coin feed-rollers, means for 40 feeding coins of different denominations to said receptacle, and automatic means controlled successively by the presence of the several coins between the rollers for indicating the respective values thereof in predetermined 45 units.

11. In a device of the class described, the combination with a sealed or locked coin receptacle, of coin feed-rollers, separate coin channels for feeding coins of different 50 denominations to different parts respectively of said rollers, means for actuating said rollers to pass said coins to said receptacle, normally disconnected means for automatically indicating the value of said respective coins, 55 and distinct means in the pathway of each coin controlled by the passage of such coin for operating said indicating means.

12. A device of the class described in which is combined two coin conveying rollers 60 inclosed within a sealed or locked inclosure, a coin receptacle in communication therewith, means for operating said rollers from without, means for automatically returning them to a normal position, a series 65 of coin-chutes for coins of different values

leading to different parts of said rollers, means in the bight of said rollers for engaging a coin when the rollers are actuated, a normally disconnected coin registering mechanism and separate means in the paths of the 70 several coins controlled by the passage of said coins respectively, for operatively connecting the same with one of said rollers, whereby the movement of said registering mechanism may be automatically varied to 75 conform to the unit value of the coin by which it is brought into action.

13. A device of the class described in which is combined two coin conveying rollers inclosed within a sealed or locked inclosure, one of said rollers being provided with a longitudinal peripheral groove, means for operating said rollers from without, means for returning them to a normal position with said groove in place to receive the edge of a 80 coin, a normally disconnected registering mechanism, a plurality of coin chutes, each for a coin of different value from the others, and separate means controlled successively by the passage of the coins in the several 85 ways for operatively connecting said registering mechanism with one of said rollers to actuate it more or less to conform to the unit 90 value of the coin.

14. A device of the class described, in 95 which is combined two coin conveying rollers inclosed within a sealed or locked inclosure, a separate coin receptacle in communication therewith, means for operating said rollers from without, means for causing 100 them to operate positively and in unison to feed a coin, one of said rollers being mounted loosely upon a shaft in operative connection with a registering mechanism, and means controlled by a passing coin for temporarily 105 connecting said roller and shaft.

15. A device of the class described, in which is combined two coin conveying rollers inclosed within a sealed or locked inclosure, a separate coin receptacle, means for 110 operating said rollers from without, means for causing them to rotate positively and in unison to feed a coin, one of said rollers being mounted loosely upon a shaft in operative connection with a registering mechanism, means controlled by a passing coin for 115 temporarily connecting said roller and shaft, and means for returning said shaft to its normal position when the coin is released from the rollers.

16. A coin registering mechanism, in which is combined two coin conveying rollers inclosed within a sealed or locked inclosure a coin receptacle in communication therewith, means for operating said rollers from 120 without, a normally disconnected coin registering mechanism for automatically registering the unit value of different coins, means controlled by the passage of a coin for operatively connecting the same with 125 130

one of said rollers, means for preventing the backward movement of said rollers while a coin is in engagement therewith, means for causing a backward movement at all other 5 times, and means for limiting such movement.

17. A coin registering mechanism, in which is combined two coin conveying rollers protected against unauthorized manipulation, 10 a sealed or locked coin receptacle in communication therewith, a plurality of coin chutes leading to said rollers for the reception of coins of different denominations, means for actuating said rollers, a normally disconnected coin registering mechanism, and separate means controlled respectively by the passage of said coins of different denominations for operatively connecting the same with said rollers, whereby 20 the movement of said coin registering mechanism may be caused to vary in conformity to the unit value of the coin by which it is brought into operation.

18. The combination with a coin receptacle, of coin feeding rollers for feeding coins of different values to said coin receptacle, a coin signal mechanism yieldingly held in a normal position, means in connection therewith for producing one or more sounds to 30 designate the several units of value of the different coins, and normally disconnected means controlled by a coin in its passage between said rollers for moving the actuator of said signal mechanism to a greater or less 35 extent, whereby a signal may be given for each unit of value of the coin deposited.

19. The combination with a coin receptacle, of coin feeding rollers having a plurality of coin chutes leading thereto for coins 40 of different values, said rollers being protected against unauthorized manipulation, a coin registering mechanism, and means controlled successively by the passage of the coins of different values, for actuating said 45 registering mechanism to automatically register their respective units of value as they are severally deposited.

20. The combination with a coin receptacle, of coin feeding rollers for feeding coins 50 of different values to said coin receptacle, a coin registering mechanism yieldingly held in a normal position, means in connection therewith for producing one or more arbitrary signs to designate the respective value 55 of the different coins, and normally disconnected means controlled by a passing coin, for moving the actuator of said registering mechanism to a greater or less extent according to the value of the coin deposited.

60 21. The combination with a coin receptacle, of coin feeding rollers protected against unauthorized manipulation for feeding coins to said receptacle, a plurality of coin chutes leading to said rollers for the introduction of 65 coins of different values, a registering mech-

anism having an actuator normally disconnected from one of said rollers, and means controlled by a passing coin for moving said actuator to a greater or less degree according to the value of the coin by the passage of 70 which it is controlled.

22. The combination with a coin receptacle, of coin feeding rollers protected against unauthorized manipulation, one of said rollers being loose upon its shaft, a plurality of 75 coin chutes for coins of different values, a coin register, an actuator therefor connected with the loose shaft of one of said rollers, a plurality of normally disconnected coin controlled dogs upon said roller for engaging 80 said shaft at varying points on its periphery upon the passage of a coin between the rollers for varying the extent of movement of said actuator, means for returning said shaft to its normal position, and means for 85 indicating the extent to which said actuator is moved with the introduction of each coin.

23. The combination with a coin receptacle, of feeding rollers for feeding coins to said receptacle, a plurality of coin-chutes leading 90 thereto for coins of different values, a registering web, means controlled by, but normally disconnected from one of said feeding rollers for intermittently feeding the said web into a sealed or locked inclosure, and independent means controlled respectively by the 95 passage of different coins for connecting said feeding mechanism to one of said rollers, whereby said web may be advanced one or more steps, according to the relative value of 100 a given coin deposited.

24. The combination with a coin receptacle, of coin feeding rollers geared to run in unison, one of said rollers being loose upon its shaft, means for yieldingly maintaining said 105 rollers in a normal position, a longitudinal groove in the periphery of one of said rollers for engaging the edges of coins, a registering mechanism in connection with the shaft of said loose roller, means for yieldingly holding 110 said shaft in a normal position, a series of coin-chutes, a corresponding series of coin-controlled dogs upon said loose roller, and separate means at different points upon the periphery of said shaft for engaging said dogs 115 when actuated by a passing coin, whereby said shaft may be rotated to a greater or less extent to move said coin registering mechanism to conform to the value of a given coin deposited.

25. The combination with a separate coin receptacle, of coin feeding rollers arranged to rotate in unison, one of said rollers being loose upon its shaft, means for yieldingly maintaining said rollers in a normal position, a longitudinal groove in the periphery of one of said rollers normally in position to engage the edges of coins introduced thereto, a series of coin chutes leading to said rollers, a series of dogs upon said loose roller opposite said 125 130

respective coin-chutes, a series of pins upon the shaft of said loose roller, each in position to be engaged by one of said dogs when abnormally moved by the passage of a coin, said pins being located in different radial planes upon said shaft, means for yieldingly maintaining said shaft in a normal position, a registering web, a vibratory lever for actuating the same, and means in connection with the shaft of said loose roller for vibrating said lever once for each coin of minimum value and a proportionate number of times for coins of larger value.

26. The combination of coin feeding rollers, a registering tape normally disconnected, means for actuating the same step-by-step into a sealed or locked coin receptacle, means controlled by the passage of a coin for connecting said tape actuating means with one of said rollers, a cylindrical coin receptacle axially pivoted within a partially inclosing case, said receptacle having an opening normally within said case, a cutter upon the edge of said opening, and a stationary cutter within said case in position to sever said tape when the receptacle is opened.

27. In a device of the class described, a cylindrical coin receptacle axially mounted within a protecting case, an opening in said receptacle, and means for locking said receptacle with its opening within said protecting case.

28. In a device of the class described, the combination of a coin registering mechanism protected against unauthorized manipulation, means for passing coins through the same to a sealed or locked coin-receptacle and a sealed or locked coin-receptacle consisting of a hollow cylinder axially pivoted within an inclosure for protecting the upper portion thereof, and an opening in said cylinder lying wholly within said protecting inclosure when said coin receptacle is in its normal position.

29. A registering mechanism inclosed within a case, an axially pivoted cylindrical coin receptacle having an opening in normal communication therewith, a protecting case for normally inclosing said opening, and means for automatically locking said registering mechanism when said coin receptacle is open.

30. In a coin registering mechanism, the combination of a registering tape, registering mechanism inclosed within a sealed or locked inclosure for moving the same step-by-step into a sealed or locked coin-receptacle, means for detachably connecting said registering mechanism within said inclosure, and means for severing the section of tape within said coin receptacle as a result of the removal of said registering mechanism.

31. The combination of coin-feeding rollers arranged to rotate in unison, one of said rollers being loose upon its shaft, coin-registering mechanism in operative connection

with said shaft, a series of curved arms pivotally mounted at one end within notches in said loose roller, means for yieldingly holding said arms with their outer edges eccentric to the axis of said shaft, each of said arms having a detent upon its inner edge adapted to engage a pin upon said shaft, and a series of pins upon said shaft located in different radial planes, each in position to be engaged by a detent during the passage of a coin between the rollers.

32. The combination of coin feeding rollers geared to rotate in unison, one of said rollers being loose upon its shaft, means for yieldingly maintaining said shaft in a normal position, a plurality of coin chutes, a plurality of curved arms pivoted at one end in notches in said loose roller, said arms lying in the respective coin paths, means for yieldingly holding said arms with their outer edges eccentric to the axis of said shaft, each of said arms having a detent upon its inner edge, adapted to engage a pin upon said shaft, a series of pins upon said shaft located in different radial planes, each being in position to be engaged by a detent during the passage of a coin between the rollers, a disk upon said shaft having a series of projecting pins bearing an arbitrary relation in their respective position to those upon said shaft, a vibratory lever located in the path of movement of the pins upon said disk, and a registering tape adapted to be actuated by said lever one or more steps according to the extent of movement of said shaft.

33. In a device of the class described, the combination of a coin receptacle comprising a hollow cylinder journaled upon its axis within a partial inclosure, said cylinder having an opening in its periphery normally within said inclosure, a primary locked or sealed inclosure, a registering tape therein arranged to be fed into said coin receptacle, means for intermittently feeding the same therein with each coin deposited and means in operative conjunction with said cylinder for severing the portion of tape projecting into the coin receptacle when the latter is opened.

34. In a device of the class described, the combination with means for conveying coins of different values to a coin receptacle, of a concentrically pivoted cylindrical coin receptacle, a coin registering tape, means for intermittently feeding the same into said coin receptacle, a stationary tape guideway serrated at its lower end and a serrated cutter upon said cylinder adjusted to pass said guideway to shear said tape when said coin receptacle is opened.

35. The combination with a coin receptacle, of a series of coin chutes for coins of different denominations, interposed means for positively feeding coins from said chutes to said receptacle, a signal mechanism, an actu-

ator, means for yieldingly holding the latter in a normal position, and separate means in operative proximity to said interposed means for positively feeding said coins, for 5 moving said actuator to a greater or less extent according to the value of the passing coin, whereby said signal mechanism may be actuated to indicate the several units of value of each coin deposited.

10 36. The combination with a coin receptacle, of a series of coin chutes for coins of different denominations, interposed means for positively feeding coins from said chutes to said receptacle, a signal mechanism, a 15 registering mechanism an actuator, and separate means in operative proximity to each of said coin chutes for moving said actuator to a greater or less extent according to the value of a passing coin, to indicate by signal and 20 record the several units of value of each coin deposited.

37. In a device of the class described, the combination of a coin receptacle, a registering web, printing mechanism in operative 25 proximity to said web, means for advancing said web step-by-step, and means interposed in the path of the coin leading to said receptacle for positively actuating said coin to control said printing and web advancing 30 mechanism to print arbitrary characters upon said web.

38. The combination with a registering tape and coin-controlled registering mechanism protected against unauthorized manipulation, of a tilting coin receptacle pivotally 35 mounted in bearings, said receptacle having an opening arranged to receive coins together with said registering tape as they are fed therein, said opening, when in its normal position, being protected by means of a suitable shield or case, and means for locking said coin receptacle with its opening so protected. 40

39. The combination with a registering mechanism inclosed within a case, of a pivotally 45 mounted tilting coin receptacle to which coin and a registering tape from said registering mechanism may be introduced through a normally shielded opening, means for locking said receptacle in its normal position, 50 and means for severing the section of tape protruding therein as a result of opening the receptacle.

In testimony whereof, we have signed this specification in the presence of two subscribers, this 15th day of June 1904. 55
